UNITED STATES PATENT OFFICE.

JESSE B. HAWLEY, OF WILMETTE, ILLINOIS, ASSIGNOR, BY MESNE ASSIGNMENTS, TO UNITED REPRODUCERS CORPORATION, OF ST. CHARLES, ILLINOIS, A CORPORATION OF NEW JERSEY.

SOUND-PRODUCING DEVICE.

Application filed July 1, 1926. Serial No. 119,807.

The present invention relates to sound producing devices, such as radio loud speakers.

Among the objects of the invention is to provide a novel sound producing means or device capable of being vibratably actuated, as by an electro-magnetic device of a loud speaker unit of a radio receiving set, and having the property of every point in the vibrating means, such as a diaphragm, whether flat or of the cone or horn shape or form, vibrating in unison and to the same extent or amplitude as the point to or at which the actuating stress may be applied or imposed upon or in the diaphragm, thus avoiding the lagging of parts as heretofore. In diaphragms, such as of the cone type or the like, where the actuation is applied at the center or apex of the cone or the like, and whether or not the rim be clamped or free, it frequently occurs that the rim parts and the parts intermediate the rim and the actuated point or part, lag in movement, and also may be moving in an opposite direction to that of the actuated point after reversal of movement thereof so that some parts might be vibrating out of phase, and so to a greater or lesser extent. Blasting, false tones, and lack of uniformity of tones in the audible range, etc., thus occur so that a true rendition of the original sounds cannot be heard.

The present invention, therefore, comprehends the avoiding of such disadvantages and the providing for a vibrating or sound emitting surface which will have all of its points moving in unison and in the same direction of actuation and also with equal or uniform movement or amplitude of movement or oscillation.

Another object of the invention is to provide such a device with means for strengthening or stiffening the sound emitting device or diaphragm and at the point or points where the actuations are applied, the strengthening means being, in a specific illustrative embodiment in the form of radial ribs or ridges extending from a central actuated point toward and to the remote portions, such as the rim, so as to give the whole diaphragm rigidity to the end of every point in the diaphragm moving in unison yet lacking any peculiar characteristic of timbre usually accompanying rigid metal resonant members.

Where large volume is desired, a large sound producer has usually been required, yet the larger the diaphragm the greater has been the lagging of the more or less remote points from the point of actuation so that the inefficiency of the device increased with the size of the diaphragm. By the present invention, a large volume of sound can be efficiently produced from larger areas than heretofore and with much purer and truer tones and renditions. This may be accomplished by constructing the diaphragmatic member with a plurality of parts or components, each of the nature of a small rigid diaphragm, yet so connected together as in a multiple or series, to form a rigid unit with the components or parts operating simultaneously and in unison. The cumulative effect of these components or parts is that of a single diaphragm of the same total area or even greater, but without the inefficient production usually incidental to the usual single large diaphragm.

Moreover, the invention also includes the application of the actuating stress or stresses at distributed points, preferably at a point for each smaller component or part, yet having but a single point of stress-application from the generating or regenerating device. The means for transmitting the stress or distribution may also be or act as a reinforcing or stiffening means. The shape of the parts or components, such as of conical forms, will give rigidity to the same, and although this may be sufficient, if it be desired, additional rigidity and reinforcing may be had by providing the parts with strengthening or stiffening ribs or the like, as above mentioned.

Heretofore, large area diaphragms of loud speakers or the like were usually circular or substantially so and occupied considerable space. If it were desirable to produce sound with a large amount of volume from a narrow space, such as an elongated opening beneath or above the cabinet of a radio receiving set, it was impossible to use the diaphragmatic type of loud speaker in such space. To produce loud or large volume sound in such space it was usual to use the horn type of speaker and shaping the mouth of the horn to fit in such space. The present invention comprehends the provision of a large area diaphragmatic type of loud speak-

er adapted to any shape my preferably arranging the smaller components of parts in series or similar relation, such as in lineal, circular or concentric series.

5 Other objects, advantages, capabilities and features are comprehended by the invention as will later appear and are inherently possessed thereby.

Referring to the drawings, Fig. 1 is a view 10 in vertical elevation of a face of a vibrating diaphragm.

Fig. 2 is a similar view of the opposite side thereof.

Fig. 3 is a transverse sectional view taken 15 in a plane represented by line 3—3 in Fig. 1 of the drawings.

Fig. 4 is a similar view taken in a plane represented by line 4—4 in Fig. 1 of the drawings.

20 Fig. 5 is a fragmentary sectional view taken in a plane represented by line 5—5 in Fig. 1 of the drawings.

Fig. 6 is a view in vertical elevation of a vibrating diaphragm composed of a pair of 25 components arranged in lineal series.

Fig. 7 is a transverse sectional view taken in a plane represented by line 7—7 in Fig. 6 of the drawings.

Fig. 8 is a longitudinal sectional view 30 taken in a plane represented by line 8—8 in Fig. 6 of the drawings.

Fig. 9 is a view in vertical elevation of a greater number of components arranged in lineal series.

35 Fig. 10 is a similar view of components arranged in circular series.

Fig. 11 is a similar view of a greater number of component parts arranged in circular series.

40 Fig. 12 is a view in vertical elevation of a pair of components arranged in concentric series or relation.

And, Fig. 13 is a transverse sectional view taken in a plane represented by line 13—13 45 in Fig. 12 of the drawings.

Referring now more in details to the drawings, the embodiments chosen to illustrate the invention are shown, reference being made first particularly to Figs. 1 to 5 inclusive of the drawings, as a disk or cone of circular form and having a number of sector shaped components or portions 1 between which are integral U-shaped ribs 2 extending from a central enlargement 3 and extending 50 toward the rim portion 4. The ribs are preferably of greater width toward the center of the diaphragm and taper toward the rim thereof. All of these parts are made from molded material such as fibrous felted pulp or the like, and are integral so that the diaphragm has no seam at any point or line whereby false nodal points would be produced. The central portion where the 55 ridges meet and where the enlargement is formed, is suitably apertured for the pass-

ing therethrough of an actuating rod or wire 5 held or secured to the part 3 by any suitable means, such as small nuts 6 and 7, as clearly shown in the drawings.

Fig. 3 shows the use of the ribs on the 70 concave side of the cone while Fig. 4 shows the ribs upon the convex side of the cone or diaphragm.

The rod 5 is connected to any suitable electro-magnetic or like device adapted to 75 effect the vibration of the rod in accordance with the sound waves or modulated carrier wave of a receiving set in radio. The longitudinal vibrations of the rod 5 will be transmitted or imposed upon the part 3 and 80 the parts integrally connected thereto. This will effect a vibration or actuation of the diaphragm parts or components 1 and also of the ribs 2, which act as stress distributing members to distribute the actuating 85 forces at different points of the device, as well as strengthening or stiffening members so that the transmission of the vibrations will be effected through these ribs to every part of the diaphragm, even to the very rim 90 4 thereof. Preferably the diaphragm is vibrated or actuated without the rim being in contact with any clamping means. It may be supported by any suitable means 95 whereby the edge of the diaphragm is free to move without any impediment. In this way every point of the diaphragm may move simultaneously and in unison with the vibrating or actuated central portion 3 so that the diaphragm acts as a rigid member 100

105 whereby the edge of the diaphragm is free to move without any impediment. In this way every point of the diaphragm may move simultaneously and in unison with the vibrating or actuated central portion 3 so that the diaphragm acts as a rigid member 100 whereby the edge of the diaphragm is free to move without any impediment. In this way every point of the diaphragm may move simultaneously and in unison with the vibrating or actuated central portion 3 so that the diaphragm acts as a rigid member 105 whereby the edge of the diaphragm is free to move without any impediment. In this way every point of the diaphragm may move simultaneously and in unison with the vibrating or actuated central portion 3 so that the diaphragm acts as a rigid member 110 whereby the edge of the diaphragm is free to move without any impediment. In this way every point of the diaphragm may move simultaneously and in unison with the vibrating or actuated central portion 3 so that the diaphragm acts as a rigid member 115 whereby the edge of the diaphragm is free to move without any impediment. In this way every point of the diaphragm may move simultaneously and in unison with the vibrating or actuated central portion 3 so that the diaphragm acts as a rigid member 120 whereby the edge of the diaphragm is free to move without any impediment. In this way every point of the diaphragm may move simultaneously and in unison with the vibrating or actuated central portion 3 so that the diaphragm acts as a rigid member 125 whereby the edge of the diaphragm is free to move without any impediment. In this way every point of the diaphragm may move simultaneously and in unison with the vibrating or actuated central portion 3 so that the diaphragm acts as a rigid member 130

Referring now to Figs. 6 to 13 inclusive, the components or parts of the diaphragm might be arranged in a series of cones or the like, a pair of the same being shown in Fig. 6. This diaphragm comprises integrally connected component parts in the form of cones 8 and arranged in lineal series. It will be understood that these components might be flat, but shaping them in the form of a cone will give them rigidity. They are 130

preferably connected integrally with an actuating bridging means 9 preferably in the form of a hollow rib and extending to the centers or apexes 10 of the cones, the member 9 having an actuating point 11. If desired, each cone may have reinforcing ribs 2, but this is not absolutely essential when the diaphragm components are made in the shape of a cone or the like.

10 In Fig. 9 is shown a longer series of cones 8 spanned by an actuating and reinforcing means or member 12 connected to central or apex points of the component parts. This member has its ends terminating over the 15 apexes of the terminal components of the series and passes over the central or apex points of the intermediate components, and is provided with a central point of actuation 13 adapted to be connected to an actuating 20 rod 5 connected to a regenerating device. It will be apparent from these constructions, that an actuation of the members 9 and 12 will be transmitted and distributed to and at the central points or apexes of the component cones 8 so that all may vibrate in 25 unison or simultaneously. By reason of the rigidity of each component owing to its conical form or by reason of its being reinforced as by ribs 2, the whole diaphragm 30 will vibrate as a single unit without lagging or flexing and thus produce a large volume of sound with pure and true tonal renditions.

Where a loud speaker diaphragm is to be 35 located to emit sound through an elongated opening in the cabinet of a radio receiving apparatus, it will be readily seen that the diaphragms shown in Figs. 6 and 9 may be readily utilized and with a result far 40 superior than to that effected by a single large circular diaphragm type of feature heretofore used.

Fig. 10 shows a similar arrangement with the component parts 8 arranged in circular 45 series, this diaphragm being made up of three components. Each component is actuated from a central point by means of an actuating spanning member 14, which also acts as a reinforcing means, the member 14 50 having a central actuating point 15 receiving the vibrations or actuations from the regenerating device and transmitting the same through the arms of the member 14 to the central points or apexes of the cones.

Fig. 11 shows a similar structure with four 55 component parts 8 arranged also in circular series and actuated by a stress distributing member 16 having radial arms terminating at the central points or apexes of the cones 60 for transmitting vibrations or actuations to these points and hence the whole body of each component part.

In Figs. 12 and 13, the component parts 65 17 and 18 are arranged in concentric series, namely, the part 7 is a small cone having

its apex 19 connected to the actuating rod 5, in the usual manner, and by reason of the part 17 being of cone formation, or the like, it is rigid and adapted when vibrated or actuated to transmit the vibrations or actuation stresses to the larger frusto-conical part 18, the actuation stresses being distributed along the connecting ridge 20, every point in this ridge acting as an actuating point for the transmission of vibrations to the frusto-conical part 18. In this way the diaphragm is of simple form and yet made rigid and strong for effecting a large volume of sound with efficient rendition.

While I have herein described and upon the drawings shown a particular embodiment of the invention, it is to be understood that the invention is not limited thereto but comprehends other constructions, details, arrangements of parts, and features without departing from the spirit thereof.

Having thus disclosed the invention, I claim:

1. A sound diaphragm of seamless integral material and comprising a stiffening portion having means for engagement with an actuating means, a sound emitting surface portion, and means for strengthening the surface portion against lag at points remote from the first mentioned portion.

2. A unitary sound diaphragm composed of a multiple of reinforced diaphragmatic parts, and means for distributing applied actuating stress to different points thereof.

3. A unitary sound diaphragm composed of a series of rigid diaphragmatic components adapted to vibrate in unison, and means connecting the same and adapted to distribute applied actuating stresses to different points thereof.

4. A unitary sound diaphragm composed of a series of rigid diaphragmatic components adapted to vibrate in unison, a rigid means extending to actuating points of said components and having an actuated point from which actuating stresses may be distributed to the actuating points of the components.

5. A unitary sound diaphragm composed of a series of integrally connected conically shaped components, and means connected to said components at actuating points thereof and adapted to transmit actuation stresses to said points.

6. A sound radiating device comprising a series of diaphragm members connected together to form a unit, a bridging member connected to said diaphragm members to transmit vibratory stresses thereto, said bridging member having means for connection to an actuating element.

7. A sound radiating device comprising a series of diaphragm members integrally connected together to form a single unit, a bridging member integrally connected to

said diaphragm members and extending ing member acting to transmit the vibra-
thereover to actuating points thereof to tions from the actuating element to the
transmit vibratory stresses thereto at said diaphragms. 10
points and to reinforce said diaphragm In witness whereof, I hereunto subscribe
5 members, said bridging member having my name to this specification.
means for connection to an actuating ele-
ment and to be vibrated thereby, said bridg-

JESSE B. HAWLEY.
